By his Attorney
John E. Hubbell

UNITED STATES PATENT OFFICE.

PHILIP D'H. DRESSLER, OF ZANESVILLE, OHIO, ASSIGNOR TO AMERICAN DRESSLER
TUNNEL KILNS, INC., OF NEW YORK, N. Y., A CORPORATION OF NEW YORK.

COMBUSTION-CHAMBER.

1,348,486.

Specification of Letters Patent.

Patented Aug. 3, 1920.

Application filed November 20, 1919. Serial No. 339,488.

To all whom it may concern:

Be it known that I, PHILIP D'H. DRESSLER, a subject of the King of Great Britain, and resident of Zanesville, in the county of Muskingum and State of Ohio, have invented certain new and useful Improvements in Combustion-Chambers, of which the following is a specification.

My present invention relates to the well-known Dressler tunnel kiln shown for example in patents of Conrad Dressler Nos. 1,023,628 and 1,170,428 granted April 16, 1912 and February 1, 1916, respectively.

In the Dressler kiln as ordinarily constructed an elongated kiln chamber is provided through which are passed cars carrying the goods or wares to be heated. At the sides of the pathway for the goods or wares are located elongated combustion chambers running lengthwise of the kiln chamber for many feet. Air and fuel are introduced to each combustion chamber adjacent one end thereof and the products of combustion flow lengthwise of the combustion chamber to an outlet at the opposite end thereof.

My present invention consists of an improved form of combustion chamber construction especially devised to eliminate or minimize difficulties arising in a Dressler kiln from the normal expansion and contraction of the parts. The various features of novelty which characterize my invention are pointed out with particularity in the claims annexed hereto and forming a part of this specification. For a better understanding of the invention, however, and the advantages possessed by it, reference should be had to the accompanying drawings and descriptive matter in which I have illustrated and described preferred embodiments of my invention.

Of the drawings;

Figure 1 is a transverse section of a Dressler kiln with the left-hand combustion chamber in section on the line 1—1 of Fig. 2,

Fig. 2 is a partial section on the line 2—2 of Fig. 1,

Fig. 3 is a partial section taken similarly to Fig. 2 but on a larger scale,

Fig. 4 is a view taken similarly to Fig. 3 showing combustion chamber sections partially separated,

Fig. 5 is a view taken similarly to Fig. 3 illustrating a modified construction, and

Fig. 6 is a section taken similarly to Fig. 5 illustrating a second modification.

In the drawings A represents the kiln chamber proper of a Dressler kiln of typical construction. The kiln chamber is inclosed by a refractory wall B and is provided at its bottom with benches C at the sides of the pathway for the goods carrying car E. On each bench C at the corresponding side of the pathway for the goods or wares F, supported by the car E, is located a combustion chamber G which runs lengthwise of the kiln and in which combustion is initiated and through which the products of combustion flow lengthwise of the kiln. The walls of each combustion chamber are formed of refractory material in the form of hollow tile H', H², H³ and H⁴, each of which extends transversely in length to the length of the kiln, and is formed with open ended channels h through which the kiln atmosphere may circulate upwardly about the combustion chamber and downward through the goods, generally as indicated by the arrows applied to the right-hand side of Fig. 1. In so far as above described, the construction illustrated is typical of the prior art.

The present invention is concerned with the formation and maintenance, notwithstanding thermal expansion and contraction of proper joints between the tile sections H', H², H³, and H⁴ arranged side by side to form each of the four walls of the combustion chamber. As shown, in Figs. 1, 2, 3 and 4 each tile section H' is formed at one edge with a shoulder or rib I adjacent the outer side and at its other edge with a rib or shoulder I' adjacent its inner side. The rib I of one section H' overlaps the rib I' of the adjacent section H'. Between the abutting and overlapping surfaces of each adjacent pair of tile sections are placed a layer J of mortar or refractory cement in the initial construction of the kiln. The provision of ribs on the adjacent tile section which overlap and which are mortared or cemented together in the initial construction of the kiln is not in itself novel, but the overlapping joint provided in the construction illustrated is novel in respect to the shape and dimensions of the overlapping ribs and in the manner in which the cement J normally sealing the joints is applied. The overlapping shoulders I and I' of ad-

adjacent sections H' have their adjacent surfaces similarly inclined to the longitudinal axis of the combustion chamber, and these shoulders extend away from the corresponding edge of the body of the tile section for a distance much greater than has heretofore been the practice. The extent to which the ribs project away from the body of the tile is made great enough so that with the maximum separation between adjacent tile sections H' which may be expected to occur in practice the ribs I and I' of adjacent tile sections will still overlap as indicated in Fig. 4. While the inclination of the overlapping surfaces of the sections to the axis of the combustion chamber involves a separation between the overlapping surfaces of the section which are drawn apart as shown in Fig. 4 with any slight angle of inclination such as that shown, the joint opening is a restricted one, and the leakage through it with the pressure normally prevailing will be comparatively slight. The inclination of the overlapping surfaces will permit this separation to occur without subjecting the tile sections to strains tending to fracture them or to tear the mortar seals apart, or to dislocate the contacting sections H' and H^3 , and H^3 and H^2 , etc. This would not be true if it were attempted to make the planes of the overlapping surfaces parallel to the axis of the combustion chamber since the character of the material out of which the tile sections H' , etc., are made and the manner in which they are made, as well as the conditions of use make it practically impossible to obtain overlapping surfaces smooth and truly parallel to one another.

While the invention is not restricted, of course, to any particular set of exact dimensions, I may say by way of example that in the actual construction illustrated in Figs. 3 and 4 the sections are so shaped and proportioned that the ribs I and I' project away from the edge of the body portion of the corresponding tile sections for about two inches. To avoid warping and fracture in the manufacture of the tile sections and under the thermal conditions to which they are subjected in use, an open ended ventilation channel h' is formed in each of the ribs I and I' to which the kiln atmosphere may circulate in operation just as it does through the channels h in the body of the tile section.

To avoid liability of the cement or mortar forming the joint J being displaced when a pair of sections are drawn apart as shown in Fig. 4, I advantageously so seal the joints that when the sections separate, the cement will adhere to one of the sections and not to the other. This effect may be produced, for example, by washing the mortar engaging surfaces of one section with silicate of soda and by washing or dusting

the mortar engaging surfaces of the other section with powdered flint. Treated in this manner the flint coating between the one section and the mortar J prevents adherence between the two, while the silicate of soda fuses when the apparatus is heated up and insures a firm adherence between the mortar and other section. Instead of, or in addition to, using silicate of soda, the surfaces to which the mortar is to adhere may be specially roughened to increase the adherence. In practice, the surfaces to which the mortar is caused to adhere should so far as is practicable be the lower of the two surfaces between which, when the mortar is placed, one surface lies above the other. By causing the adherence of the mortar to one of the two adjacent tile sections only, there is less liability of the mortar being displaced when the sections pull apart, and the avoidance of such displacement insures a practically gas-tight joint when by a subsequent temperature change or by manipulation the sections are brought together again. If the mortar adhered to both surfaces and had to be broken apart when the sections separate or did not adhere to either the mortar would sometimes interfere with the return of the sections from the condition illustrated in Fig. 3 to that illustrated in Fig. 4.

The sections H^2 are formed with overlapping ribs and have joint forming provisions exactly similar to those employed in the section H' and this is true also of the various sections H^3 and H^4 . Indeed, in practice, the various sections H' , H^2 , H^3 , and H^4 are of the same cross-section and are made in the same pipe molding machine.

The results obtained with the overlapping joint construction shown in Figs. 1, 2, 3, and 4 may obviously be obtained with differently shaped ribs. For example, as shown in Fig. 5 each of the tile sections HA is formed at one edge with a central rib I^5 having its opposite side inclined toward one another, and is formed at its opposite edge with a pair of ribs I^6 having adjacent sides inclined away from one another and proportioned to receive between them rib I^5 of an adjacent section HA . Similarly, as shown in Fig. 6, each tile section HB may have two ribs I^6 at each of its opposite edges and both adjacent one side of the section, while the adjacent section has similar ribs I^7 at its opposite edges both at the opposite side of the section from that at which the ribs I^6 are located.

While in accordance with the provisions of the statutes I have illustrated and described the best form of my invention now known to me, it will be apparent to those skilled in the art that changes may be made in the form of the apparatus disclosed without departing from the spirit of my invention as set forth in the appended claims.

Having now described my invention, what I claim as new and desire to secure by Letters Patent, is:

1. In a tunnel kiln, a combustion chamber having its walls formed of sections of refractory material separated by joints transverse to the length of the sections and having shoulders which overlap at the joints to an extent greater than the separation of the sections resulting from normal changes in the kiln chamber and having the overlapping surfaces of the shoulders similarly inclined to the longitudinal axis of the chamber.
2. A combustion chamber for tunnel kilns having its walls formed of sections of refractory material separated by joints transverse to the length of the section and having shoulders which overlap at the joints each of said sections having one or more open-ended ventilating channels formed in its body portion and an open-ended ventilating channel formed in each of its overlapping
3. A combustion chamber for tunnel kilns having its walls formed of sections of refractory material separated by joints transverse to the length of the sections and having shoulders which overlap at the joints and a refractory filling between the adjacent sections adhering to one but not the other of adjacent sections.
4. A combustion chamber for tunnel kilns having its walls formed of sections of refractory material separated by joints transverse to the length of the sections and having shoulders which overlap at the joints and a refractory mortar filling between adjacent sections cemented to one of said sections and separated from the other of said sections by non-cementitious material.

Signed at Detroit in the county of Wayne and State of Michigan this 14th day of November A. D. 1919.

PHILIP D'H. DRESSLER.
